D. 366,624 1/1996 Collins D10/70
2,824,373 2/1958 Bottenfield ..... 33/3 A*Primary Examiner*—Antoine Duval Davis**CLAIM**

The ornamental design for a three-dimensional children's shoe sizer, as shown and described.

DESCRIPTION

FIG. 1 is a front elevational view of the three-dimensional children's shoe sizer showing my new design;

FIG. 2 is a rear elevational view thereof;

FIG. 3 is a right view thereof;

FIG. 4 is a left view thereof;

FIG. 5 is a top plan view thereof; and,

FIG. 6 is a bottom plan view thereof.

The broken line showing is for illustrative purposes only and forms no part of the claimed design.
